HYDRODYNAMIC BATHTUB

Charles S. Benson, 11944 Montana Ave.,
West Los Angeles, Calif. 90049

Filed Jan. 23, 1969, Ser. No. 15,473

Term of patent 14 years

Int. Cl. D23—02

U.S. Cl. D23—55

FIG. 1

FIG. 2

FIG. 3

FIGURE 1 is a fragmentary perspective view of a hydrodynamic bathtub showing my new design;

FIGURE 2 is a top plan view thereof; and

FIGURE 3 is a cross sectional view taken on line 3—3 of FIGURE 2.

I claim:

The ornamental design for a hydrodynamic bathtub, substantially as shown.
